UNITED STATES PATENT OFFICE.

VERE B. BROWNE, OF TARENTUM, PENNSYLVANIA.

OPEN-HEARTH FURNACE.

1,393,493.

Specification of Letters Patent. Patented Oct. 11, 1921.

Application filed June 28, 1919, Serial No. 307,469. Renewed August 8, 1921. Serial No. 490,809.

To all whom it may concern:

Be it known that I, VERE B. BROWNE, a citizen of the United States, and a resident of Tarentum, in the county of Allegheny and State of Pennsylvania, have made a new and useful Invention in Open-Hearth Furnaces, of which the following is a specification.

This invention relates to improvements in open hearth furnaces and has as an object the provision of certain new arrangements whereby powdered fuel (such as powdered coal) may be used with a material decrease in the clogging of the checkers over that occurring in the present arrangements.

A further object is the provision of a furnace of the above type in which the checker work is located entirely above the ground level thus enabling relatively easy repairs and renewals.

These, as well as other objects which will readily appear to those skilled in this particular art I attain in the furnace described in the specification and illustrated in the drawings accompanying and forming a part of this application.

In the drawings, Figure 1 is a longitudinal vertical section of a furnace embodying this invention and Fig. 2 is a longitudinal horizontal section taken at a point just above the hearth.

The furnace consists of a hearth 3 of ordinary construction supported on the foundation 4 and provided with a roof 5. A checker work regenerator 6 connects with one end of the hearth by means of flue 7 of novel construction while a checker work regenerator 8 connects with the other end of the hearth by means of a flue 9 of similar novel construction.

Powdered fuel, such as powdered coal, is forced into the combustion chamber above the hearth through ports or nozzles 10 (preferably water cooled) of suitable size and number and which are positioned so as to discharge the fuel at the proper angle into the combustion chamber.

Each of the flues 7 and 9 is constructed with a central wall 11 having a port 12 extending therethrough. The wall thus converts each flue into an up and down-take having a connecting port. The space below the bottom of the port is a dead air space and serves to collect the ash and other solid matter carried through the flue toward the

checker brick with the products of combustion. Each of the separate chambers of the separator is provided with tracks 13 for slag cars 14.

The checker work will merely be used to regenerate the air and if desired each end of the furnace may be provided with an extra checker work 15 in order to serve as a spare regenerator. If it becomes necessary to clean out or repair one of the main regenerators without stopping the operation of the furnace this may be done by opening up port 16 which connects spare regenerator 15 with one of the flues 7 or 9 and when this is done opening 17 will be closed as shown at 18, Fig. 2. The furnace is provided with a suitable stack 19, valves 20 and 21 and dampers 20^a, 20^b and 20^c for reversing the operation of the regenerators.

Each regenerator is provided with a cleaning door indicated by circle 22 and since these are located above the ground level 23 the checker work may be repaired or renewed from time to time without dismantling the entire regenerators as is now customary.

The products of combustion passing through the flue to the regenerator in striking the partition between the up and down-take has its direction changed and the solids tend to fall down along the partition wall to the dead air space at the bottom of the down-take. In crossing through the port 12 to the up-take the direction is again changed and the solids impinging on the far wall of the up-take tend to fall down along said wall to the dead air space at the bottom of the up-take. The flue with its central partition, which serves as a baffle, acts in the nature of a separator. The solids and heavy particles contained in the gases fall into the dead air spaces and the effective efficient life of the regenerators is increased over those now in use. The terms up and down-take as just used apply to each flue when it is being utilized to convey the products of combustion to a regenerator. When these flues are used for conveying heated air from the regenerator to the hearth or to the combustion chamber above the hearth the portions of the flue of course will be reversed and what before was the down-take becomes the up-take, etc.

In accordance with the provisions of the patent statutes I have described the principle of the operation of my invention, to-

gether with the device which I now consider to represent the best embodiment thereof, but I desire to have it understood that the device shown is only illustrative and that the invention can be carried out in other ways.

Having thus described my invention what I claim is—

1. The combination with a hearth, of regenerators arranged to be alternately utilized and central walls each provided with a through port to form separators between said hearth and said regenerators.
2. The combination with a hearth, of regenerators arranged to be alternately utilized and separators between said hearth and said regenerators each having an up and down-take formed by a central wall baffle provided with a through port.
3. The combination with a hearth of a regenerator arranged at each end of said hearth, an additional regenerator located adjacent one of the first-mentioned regenerators, and a central wall to form a pair

of separating chambers between each regenerator and the hearth.

4. The combination with a hearth, of regenerators arranged to be alternately utilized and located above the ground level and a separator between said hearth and each regenerator provided with two dead air pockets.

5. The combination with a furnace hearth, of regenerators arranged to be alternately utilized, separators arranged between said hearth and said regenerators, and means for discharging powdered fuel into said furnace through the roof thereof and at an inclination to the hearth.

6. The combination with a hearth of a regenerator arranged at each end of said hearth, and a central wall to form a pair of separating chambers between each regenerator and the hearth.

In testimony whereof, I have hereunto subscribed my name this 25th day of June, 1919.

VERE B. BROWNE.
